CARRYING CASE FOR A PHONOGRAPH OR SIMILAR ARTICLE

Charles F. Pohlmann, Syracuse, N.Y., assignor to General
Electric Company, a corporation of New York

Filed Apr. 30, 1962, Ser. No. 69,891

Term of patent 14 years

(Cl. D87—5)

FIG. I.

FIG.2.

FIG.3.

FIG.4.

FIG.5.

FIG.6.

FIG. 1 is a top perspective view showing my new design of a carrying case for a phonograph or similar article, with the cover in an open position;

FIG. 2 is a reduced side elevational view, with the cover in a closed position;

FIG. 3 is a reduced top plan view thereof;

FIG. 4 is a reduced side elevational view, showing the side opposite that shown in FIG. 2;

FIG. 5 is a reduced front elevational view; and

FIG. 6 is a reduced rear plan view.

The bottom of the case is substantially the same in appearance as the top shown in FIG. 3 except for the provision of a plurality of bumper feet as seen in FIGS. 2, 4, 5 and 6.

The dominant features of my design reside in the portions shown in full lines.

I claim:

The ornamental design for a carrying case for a phonograph or similar article, substantially as shown and described.
